UNITED STATES PATENT OFFICE.

EDWARD E. STEDMAN, OF RAVENNA, OHIO.

IMPROVEMENT IN CLASPS FOR PREVENTING INGROWING OF TOE-NAILS.

Specification forming part of Letters Patent No. 137,106, dated March 25, 1873.

To all whom it may concern:

Be it known that I, EDWARD E. STEDMAN, of Ravenna, in the county of Portage and State of Ohio, have invented an Improvement in a Clasp or Tip for Preventing Ingrowing Toe-Nails, of which the following is a specification:

My invention consists of an improvement in tip, for which I have a patent—No. 132,872—bearing date of November 5, 1872.

The improvement is in the application of a wire spring connecting the two hooks, the formation of which is fully illustrated in the accompanying drawing, making the clasp self-adjustable, and thus obviating the difficulty of fitting each one expressly for the case.

With the exception of said spring substituted for the solid inflexible metallic connection between the two hooks, the clasp remains substantially the same as specified and claimed in Letters Patent bearing number and date above referred to.

I claim as my invention—

The attachment of a spring, connecting the two hooks which pass under the corners of the nail, as above specified.

EDWARD E. STEDMAN.
